LIQUID FEED CARBURETOR

Gerhard Gerson, Keeego Harbor, Mich., assignor
to Phillips Petroleum Company, a corporation
of Delaware

Application August 8, 1941, Serial No. 406,064

1 Claim. (CL 261—69)

This invention relates to a carburetor for internal combustion engines, and more particularly, it relates to a carburetor for utilizing fuels having a wide boiling range.

The present invention has for its purpose to provide a carbureting arrangement which is adapted to deliver high pressure fuels such as natural gasoline and butane to the intake manifold in liquid phase without the occurrence of vaporization or vapor lock in the lines and connections between the fuel tank and the carburetor jet. The carburetion of fuels of this type presents a peculiar problem since they contain constituents which are either entirely gaseous at ordinary temperatures and pressures as in the case of butane, or exist simultaneously in the liquid and gaseous phase as in the case of natural gasolines. Fuels of the latter type ordinarily consist of a mixture of heavy and relatively light hydrocarbons, the light fractions consisting mainly of mixtures of propane and butane and are stored in tanks under their own vapor pressure, the light fractions remaining in solution with the heavier fractions under the existing superatmospheric pressure.

Due to the high volatility of fuels of the aforementioned type, carburetors of conventional design are eminently unsuitable as means for getting the fuel from the tank to the engine in the proper proportions. Vaporization will occur immediately as the pressure on the fuel is reduced. The fuels are particularly desirable for internal combustion engines due to their exceptionally high anti-knock value and it has been the practice to utilize gas carburetors for their carburetion which completely vaporize the fuel after it leaves the tank. These arrangements are particularly bulky and expensive while the present invention provides an arrangement whereby the fuel is efficiently and accurately carbureted in the liquid phase without the occurrence of vapor lock.

My invention has for its primary object the provision of a carburetor apparatus for utilizing volatile compounds having a wide boiling range as motor fuel for internal combustion engines.

Another object of this invention is to provide a carburetor for utilizing a variety of fuels including natural gasolines, butane, and the like.

A still further object is to provide a carburetor which will operate with fuels of varying vapor pressures without requiring a manual change of adjustments.

These and additional objects and advantages of this invention will be apparent to those skilled in the art by reference to the following descrip-

tion and annexed drawing which pertains to preferred embodiment of my invention; wherein the figure is an elevation view of my invention, partly in cross section.

- 5 Referring to the figure I have denoted therein a carburetor barrel or gas-air mixing tube by reference numeral 10. A venturi 11 is positioned in barrel 10 above a throttle valve 12, and is provided with a plurality of openings 13 which communicate with a passage 14. Throttle valve 12 is mounted on a shaft 15 which extends through the barrel and is connected to a means (not shown) which regulates the valve's opening and closing in a manner common to the art.
- 15 A conduit 16 connects with passage 14 and with a chamber 51 which is formed in a diaphragm housing 50 connected to the lower portion of barrel 10. The chamber 51 is formed in the diaphragm housing between the outer portion thereof and a diaphragm plate 52 which is contained within the housing. The chamber 51 communicates with openings 13 of the venturi 11 through conduit 16 and passage 14. A valve stem 53 is positioned within the housing and is secured to the diaphragm plate. Stem 53 extends through the central portion of housing 50 and barrel 10 and is free to move upon movement of plate 52. A needle valve 24, which is secured to stem 23, regulates the opening and closing of a fuel induction orifice 23 which is provided in a preferably non-metallic discharge end 26 of a conduit 27. The discharge end 26 is formed of a synthetic resin glass or other plastic to prevent premature vaporization in the tube due to manifold heat.
- 20 35 This conduit communicates with the interior of a shut-off valve casing 28 which contains a master valve for shutting off flow of fluid from the tank to the outlet orifice when the motor has stopped.
- 40 A compression spring 54 of any desired strength is contained in housing 50 and in a hollow extension 55 of the housing. The spring is positioned between the outer face of diaphragm plate 52 and a collar 56 fixed in extension 55. An air bleed valve 57, which is closed when needle valve 24 is closed, is formed on the outer end of stem 53 and extension 55 to assist in controlling the opening and closing of the needle valve. The air bleed valve influences the suction effect on the diaphragm to compensate for pressure fluctuations below the main throttle valve. A lever 58 which is pivotally mounted on extension 55 is connected at the top to stem 53 and at the bottom to a cable 59 which is connected at the other end to a pivotally mounted eccentric element 60. It will be noted from the drawing that a roller

61 is employed to give a desired direction of the movement of lever 63, however, it is to be understood that any suitable type of linkages, cables, and the like which will produce the desired movement of lever 63 may be used satisfactorily. Element 60 is pivotally attached to a stem 62 which in turn is secured to a diaphragm plate 63 which is contained within a diaphragm housing 64. A compression spring 65 of any desired strength is positioned about stem 62 between the diaphragm housing and plate 63. Spring 65 is adjusted to maintain plate 63 in a predetermined position against the pressure of the fuel which acts on the opposite side of the plate from spring 65 through a branch conduit 66 which communicates with the right hand portion of the diaphragm housing and with fuel conduit 34. It will be noted in the drawing that a stem 67 is used to open shut-off valve 28 when the internal combustion engine, for which this carburetor is adapted, is started up. Stem 67 is urged downwardly by a lever 68 which is controlled and operated from a remote source in a well-known manner.

An oil chamber is formed in the lower portion of the valve casing 28 which communicates with the lubricating system of an internal combustion engine (not shown) through a conduit 38. It will be noted from the drawing that a passage 39 is provided in barrel 10. This passage communicates with conduit 27 and with the interior of 10. Where the passage connects with the barrel it is restricted by an adjustment screw 40. A shut-off valve 41 is provided in the passage 39 to control the opening thereof. Shut-off valve 41 is operated from throttle valve shaft 15 through the medium of a pivoted lever 43 by means of a linkage 42 shown in dotted lines. One end of the lever 43 bears on the end of the shut-off valve 41, while the other end is yieldingly connected with linkage 42. It will be further noted that when the internal combustion engine is idling or at very low loads, valve 41 is open and fuel enters barrel 10 through passage 39. At other loads of the engine when throttle 12 is open, valve 41 will be completely closed.

In the operation of the device it will be noted that the fuel induced into the intake manifold does not begin to vaporize normally until it has been inducted into mixing tube 10. When the internal combustion engine is operating, master valve 28 is regulated by the pressure of the oil in the lubricating system in the manner described. The amount of fuel which is inducted into carburetor barrel 10 through conduit 27, orifice 25, and needle valve 24 is controlled by the suction created from the passage of air through venturi 11. The needle valve is also controlled to compensate for changes in the vapor pressure of the fuel. The pressure of the fuel in conduit 36 acts upon diaphragm 63 of diaphragm housing 64 through conduit 66, urging plate 63 to the left against the action of spring 65. As stem 62 is secured to plate 63, it also moves to the left, causing element 60 to rotate in a clockwise direction. Upon the rotation of element 60, cable 59 moves the lower portion of lever 63 to the left 59 moves the lower portion of lever 63 to the right which in turn pivots the upper portion of lever 63 to the right. As the upper end of lever 63 is attached to valve stem 53, the stem moves to the right with the action of spring 54 and against the suction caused by the passage of air through venturi 11. This tends to close needle valve 24 and restrict the amount of fuel leaving orifice 25, allowing the proper proportion of fuel and air to enter the intake manifold. By employing my ap-

paratus, I am able to maintain the volume of fuel entering barrel 10 at a desired amount regardless of an increase in vapor pressure. On the other hand, should the vapor pressure of the fuel decrease to below the normal operating range, my device would operate to allow needle valve 24 to open a greater amount. In the use of high pressure fuels, vaporization does not occur in the conduit 34, since the fuel is subjected to the vapor pressure of the fuel at the source of fuel supply. By means of my device, accurate metering is possible regardless of change in supply pressure due to variation in the temperature of the fuel. It will be apparent that the amount of fuel entering barrel 10 is a function of the area of the orifice opening and the vapor pressure of the fuel. When needle valve 24 is open, air is admitted through air bleed valve 57 into chamber 51 to reduce the amount of suction acting on diaphragm plate 63, and consequently to reduce the movement of diaphragm 63 and of needle valve 24 during the operation of the internal combustion engine. Valve 57 makes possible a smooth change of needle valve movement throughout the range of speeds for all loads, which facilitates the proportioning of the amounts of fuel and air induced to the intake manifold. In starting the internal combustion engine, stem 67 is urged downwardly by lever 68, opening master valve 28, and thus allowing fuel in conduit 34 to enter conduit 27. As throttle plate 12 is closed, valve 41 is open, and fuel flows into barrel 10 through passage 39, and thence to the intake manifold.

From the foregoing, it is believed that the operation and advantages of the apparatus for practicing my instant invention will be readily comprehended by persons skilled in the art. It is to be clearly understood, however, that various changes in the apparatus shown and described may be resorted to without departing from the spirit of the invention, as defined by the appended claim.

I claim:

In a carburetion system for internal combustion engines adapted for handling liquid fuel of relatively high vapor pressure including a mixing tube having a venturi, a throttle valve in the mixing tube, a fuel supply, an outlet orifice for delivering liquid fuel into the mixing tube, below the throttle valve, means for maintaining said fuel in liquid phase from the fuel supply to the outlet orifice comprising a fuel valve for said orifice, a diaphragm housing, a diaphragm in said housing operably connected with the fuel valve and forming a chamber on one side communicating with the mixing tube at the venturi, the opposite side being in communication with the atmosphere, spring means urging said fuel valve closed, so that suction induced by air flow through the venturi communicated to the diaphragm will open the fuel valve against the action of said spring means, an air bleed valve in said chamber connected with the fuel valve for influencing the suction effect communicated to the diaphragm from the venturi, to compensate for pressure fluctuation on the fuel outlet below the throttle valve, pressure responsive means communicating with the fuel supply upstream of the outlet orifice, spring means acting on said pressure responsive means in opposition to fuel pressure, and means operably connecting the pressure responsive means with the fuel valve to vary the degree of loading on said fuel valve in accordance with variation in pressure in the fuel supply.

GERHARD GERSON.
